PASTE TUBE CLOSURE MEANS

Clyde J. Peak, San Francisco, Calif.

Application September 23, 1941, Serial No. 412,034

4 Claims. (Cl. 221—60)

This invention relates to improvements in closure means for collapsible tubes of the type employed for merchandising toothpaste, shaving cream, paints and other fluid or semi-fluid materials.

The primary object of the present invention is to provide a novel closure means for such tubes which is of a type to be economically produced and which functions automatically upon the application of pressure to certain parts thereof, to open and upon release of such pressure closes to shut off the flow of material.

Another object of the invention is to provide in a collapsible tube, a closure element upon an end of the tube comprising a yieldable body overlying an opening in the end of the tube and having a slit through which the contents of the tube may be ejected and flexible co-acting jaws normally functioning to overlie and press against the flexible material at the side of the discharge slit to maintain the same closed, said jaws being automatically separated upon the application of pressure to opposite sides of the closure element.

The invention will be best understood from a consideration of the following detailed description taken in connection with the accompanying drawing, it being understood, however, that the invention is not to be considered as limited by the specific illustration or description, but that such illustration and description constitute a preferred embodiment of the invention.

In the drawing—

Fig. 1 is a sectional view on an enlarged scale, taken on a line extending longitudinally of the tube and transversely of the closure element, showing the parts of the closure element on an exaggerated scale.

Fig. 2 is a view of the closure end of the tube showing the closure device in section similarly to Fig. 1 but with the co-acting jaws thereof separated to permit the discharge of material from the tube.

Fig. 3 is a view of the end of the tube as initially prepared for the application of the closure element thereto.

Fig. 4 is a view in plan of the adhesive sheet which is applied over the end of the tube and of the rubber sheet carried by the adhesive sheet.

Fig. 5 is a view in plan of the resilient plate which is applied over the adhesive sheet and which carries the resilient separable jaws.

Fig. 6 is a view of the cap which is applied over the co-acting ends of the jaws.

Referring now more particularly to the drawing the numeral 1 generally designates a por-

tion of one end of a foldable or collapsible tube of the type commonly employed for toothpaste, shaving cream and the like and to which the closure element embodying the present invention is applied.

In carrying out the present invention the collapsible tube is prepared by being cut straight across as shown in Fig. 3, and at the central part of the two parallel end edges thus formed, there is cut out the notch or opening 2. The two portions of the end of the tube upon the two sides of the notch 2 are then folded or crimped over, as indicated at 3, so that material can be expelled from the tube only through the notch portion 2. 10 In addition to preventing the material from escaping from the tube upon the two sides of the notch 2, this backfold also provides an edge to be gripped by the cap or closure hereinafter described.

There is next prepared a strip or sheet of material 4 having upon one side face a suitable adhesive coating 5 by which the strip or sheet can be secured firmly to the body of the tube 1. A material such as the well known adhesive tape might be employed for the formation of the sheet 4. The sheet or strip 4 is then provided with an elongated opening 6 of a width corresponding to the width of the notch 2 and of substantial length so that when the sheet 4 is secured over the end of the tube 1 to have substantially one-half of the adhesive surface secured against a side of the tube, the ends of the opening 6 will match up with the inner part of the cut out or notch 2.

There is next applied to the adhesive face 5 of the sheet 4, a strip of rubber 7 having a sufficient length and width to completely cover the opening 6 and this strip of rubber sheet is provided with a slit 8 which is located substantially mid-way between the ends of the opening 6 and extends across the opening as shown in Fig. 4. The strip of rubber 7 will be firmly secured between the sheet 4 and the body of the tube and will, of course, be folded across the opening 2 with the sheet 4 and it is arranged so that the slit 8 will align with the end edge of the tube and extend across the cut out portion 2 from one side to the other.

The numeral 9 generally indicates an elongated sheet of metal having a width corresponding to the width of the tube body 1 and having a certain amount of resiliency or spring. This metal sheet or plate is provided substantially mid-way of its ends with the transversely extending roughened surface portion 10 and the sheet is

designed to be folded transversally mid-way between its ends to receive the end edge of the tube and the bodies 4 and 7 applied thereto.

The metal plate 9 has cut therethrough the spaced parallel longitudinally extending slots 11 and the material between these slots is then cut transversely as indicated at 12, along the transverse center of the plate, so as to provide the two resilient or spring jaws 13.

When the plate 9 is bent or folded transversally along the line of the cut or split 12 it is then folded across the end edge of the tube and the roughened part 10 at the sides of the tongues or the jaws 13 are pressed tightly together so as to grip firmly between them or between opposing faces of the plate, the folded portion 3 of the tube and the bodies 4 and 7. This arrangement is clearly shown in Fig. 1 where the parts are illustrated on an exaggerated scale to clearly show their assembled relation. It will thus be seen that the plate 9 forms a cover cap which in the portion adjacent to jaw 13 firmly grips the end edge of the tube upon two sides of the cut out 2 and then extends over the sloping sides of the tube forming the wing portions 14 which may lie against the adjacent walls of the tube or be slightly spaced therefrom as may be found to be most suitable. It will of course be understood that adjacent ends of the jaws 13 will also be bent so as to constantly press together over the rubber body 7 at the slit 8 so as to hold the edges of the slit of the rubber body together and thus prevent any of the material in the tube escaping therefrom. As shown in Figure 2 when the lower ends or remote ends of the portion 14 of the metal plate 9 are pressed inwardly toward the sides of the tube the part of the plate 9 upon each side of the slot 11 and which is clamped over the end edge of the tube, will flex but the jaws 13 will be sprung apart and consequently when tube is pressed the material thereof will force itself against the rubber body 7 causing the latter to stretch and thus separate the edges of the slit 8 so that the material will escape and in the form of a ribbon.

The metal cap 15, shown in Fig. 1 and Fig. 6, comprises merely a piece of material bent to have a substantially U-shaped cross-section and this is slipped over the bend in the plate 9 to cover the ends of jaws 13 and is frictionally held in place. This cap will be applied, of course, when the tube is packaged for sale and also, when it has been put in use, and after a desired quantity of the contents of the tube has been expelled therefrom.

In the carrying out of the present invention the sheet 4 may be made, if desired, so cover the entire end of the tube and the resilient sheet or strip 7 may or may not be used as found desirable. The use of this rubber sheet is made when an extra tight sealing of the opening is desired or where the contents of the tube may be of acid character.

Also it is to be understood that while the jaws 13 have been shown as being of equal length and coming together in the center of the discharge opening they may be of unequal length or use

my be made of only one jaw if desired in which case the contents of the tube may more easily be spread over a flat surface.

What is claimed is:

1. In a dispensing collapsible tube, a tube body formed at one end to have opposite sides disposed in contacting relation forming a straight body, said transverse edge having a notch cut therein at the central part of the edge, a sheet of stretchable material covering the end portion of the tube in which the notch is formed and having a slit coinciding with the notch, a pair of resilient jaw members supported upon the said end of the tube upon opposite sides of the notch and having free ends in contacting relation over the slit portion of said body of stretchable material, and means for springing the free ends of said jaws apart to permit the contents of the tube to be extruded through the slit of the stretchable body.

2. In a collapsible paste tube of the character stated, a tube body formed at one end to have opposite sides disposed in contacting relation forming a straight transverse body, said edge having an outlet opening cut therein at said edge, a sheet of stretchable material secured across said edge to cover said opening and having a slit coinciding with the opening through which material may be expelled, and resilient jaw members carried by the tube and engaging over said sheet and slit to normally close the slit, said jaw members being separable to facilitate the extrusion of the contents of the tube through said slit.

3. In a collapsible paste tube of the character stated, a tube body formed at one end to have opposite sides disposed in contacting relation forming a straight transverse edge, said body having a notch cut therein at the central part of the edge to form a discharge opening, a sealing strip secured across said edge from one side of the tube to the other, said strip having a slit coinciding with said opening, a sheet of rubber secured between the strip and the edge of the tube and covering the said opening and also covering the slit in the strip, said sheet of rubber having a slit formed therein to extend transversely of the first slit and to extend across the notch parallel with the edge of the tube, and a pair of resilient jaws mounted upon the tube upon opposite sides of the notch and engaging together over the slit of the rubber sheet to maintain the rubber sheet in position and prevent opening of the slit therein, said jaws being separable to permit the slit to open and to permit the extrusion of the contents of the tube.

4. A structure as set forth in claim 3, including a plate body bent transversely to form two side portions and disposed across and having the said edge of the tube between the two side portions, the said side portions having gripping relation with said edge, said jaws being an integral part of said plate body and the opposite sides of the bent plate body being moveable relative to the tube to facilitate relative shifting of the ends of the jaws.
